CLAIM

The ornamental design for a stuffed animal baby blanket, as shown and described.

DESCRIPTION

FIG. 1 is a front perspective view of a stuffed animal baby blanket embodying the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view thereof with the blanket partially folded;

FIG. 9 is front elevational view thereof with the blanket folded;

FIG. 10 is a front elevational view thereof with the blanket portion folded vertically toward the pocket opening in the design;

FIG. 11 is an enlarged front elevational view thereof showing the blanket fully inserted into the pocket; and,

FIG. 12 is an enlarged front perspective view thereof showing the blanket fully inserted into the pocket.

The broken lines depict portions of the stuffed animal baby blanket that form no part of the claimed design.
